COMBINED TRACTOR RADIATOR COVER
AND HOOD

Walter L. Brockway, Auburn Township, Geauga
County, Ohio, assignor to Adrian Medert,
trustee, Cleveland, Ohio

Application April 13, 1950, Serial No. 9,176

Term of patent 14 years

(Cl. D14—18)

To all whom it may concern:

Be it known that I, Walter L. Brockway, a citizen of the United States, residing at Auburn Township in the county of Geauga and State of Ohio, have invented a new, original, and ornamental Design for a Combined Tractor Radiator Cover and Hood, of which the following is a specification, reference being had to the accompanying drawing, forming a part thereof, in which Figure 1 is a perspective view of a combined tractor radiator cover and hood showing my new design; Figure 2 is a top plan view; Figure 3 is a side elevational view; and Figure 4 is a front elevational view.

I claim:

The ornamental design for a combined tractor radiator cover and hood, as shown.

WALTER L. BROCKWAY.
